UNITED STATES PATENT OFFICE.

ERNEST A. SCHROEDER AND JOHN N. TOOKER, OF SYRACUSE, NEW YORK, ASSIGNEES
TO CHURCH & DWIGHT COMPANY, OF NEW YORK, N. Y., A CORPORATION OF MAINE.

CARTON-OPENING MACHINE.

1,220,566.

Specification of Letters Patent. Patented Mar. 27, 1917.

Application filed July 20, 1915. Serial No. 40,823.

To all whom it may concern:

Be it known that we, ERNEST A. SCHROEDER and JOHN N. TOOKER, citizens of the United States, and residents of Syracuse, in the county of Onondaga and State of New York, have invented a new and useful Improvement in Carton-Opening Machines, of which the following is a specification.

The object of this invention is to provide a machine having mechanisms for supplying collapsed cartons, feeding the collapsed cartons one by one to a predetermined point, opening up the carton, folding the flaps at one end of the carton together, sealing said flaps, and finally ejecting the carton with one end sealed and the other end opened ready for filling.

The invention consists in certain improvements in the construction, form and arrangement of the several parts of a carton handling machine, whereby the above object may be carried out in a simple, rapid and effective manner.

The invention more specifically comprises an endless carrier arranged to feed the collapsed cartons upwardly along a carton supply magazine into position to be fed into the machine; suction means for feeding in and opening up the collapsed cartons one by one and holding the carton in its opened position while a former, traveling in an endless path, is forced into the carton; means for moving the carton with its former along the machine while the flaps at one end of the carton are subjected to successive folding operations, means being employed for applying an adhesive to the under side of the last-folded flap and for exerting pressure on the carton for holding the flaps in their folded position to permit the permanent sealing of the flaps without distortion of the carton.

Means are also employed for blowing the carton from its former at the delivery point and for conveying the former back to its original position ready to be forced into another carton where the cycle of operations may be repeated.

Means are also provided for permitting a rapid operation of the machine by causing the feeding in of a collapsed carton at the

same time that a preceding carton is being opened up.

A practical embodiment of our invention is represented in the accompanying drawings, in which—

Figure 1 is a left side elevation of the machine,

Fig. 2 is a front end elevation,

Fig. 3 is a right side elevation,

Fig. 4 is a rear end elevation,

Fig. 5 is an enlarged top plan view,

Fig. 6 is a vertical central section taken from front to rear through the machine with the several parts in the positions which they assume when the carton feeding and opening mechanism is at the limit of its forward movement,

Fig. 7 is a continuation of Fig. 6, from the line X—X to the floor line,

Fig. 8 is a detail section showing the means for controlling the movement of the feeding mechanism for the collapsed cartons,

Fig. 9 is a detail view corresponding to Fig. 6, with the several parts in the positions which they assume when the carton feeding and opening mechanism is at the limit of its rearward movement,

Fig. 10 is a detail horizontal section on an enlarged scale taken in the plane of the line A—A of Fig. 1, with the parts in the positions shown in Fig. 6,

Fig. 17 is a detail vertical transverse section taken in the plane of the line C—C of Fig. 6.

Fig. 18 is a detail section showing the 5 guiding means for the former in its movement rearwardly to the pressure magazine.

Fig. 19 is a top plan view of the collapsed carton,

Fig. 20 is a bottom plan view of the same, 10 Fig. 21 is an end view of the collapsed carton,

Fig. 22 is a perspective view showing the carton opened,

Fig. 23 is a detail perspective view of the 15 opened carton showing the first fold,

Fig. 24 is a similar view showing the second fold,

Fig. 25 is a similar view showing the third fold, and

20 Fig. 26 is a view in perspective of the carton showing the fourth and final fold.

The carton comprises a body portion having four sides, 1, 2, 3, 4, and four flaps, 5, 6, 7, 8, at one end thereof, and four flaps 9, 10, 25 11, 12, at the other end thereof.

Several coacting mechanisms are employed to act upon the cartons to first feed the cartons along a supply magazine in their collapsed condition; to feed the cartons one 30 by one into the machine in their collapsed condition; to operate upon each carton to open the same; to fold and seal the flaps at one end thereof; to exert pressure on the carton and to eject the carton with the flaps 35 at the other end thereof unfolded so that the carton will be ready for filling.

The construction, form, arrangement and operation of the several mechanisms will now be described.

40 A suitable drive shaft 13 is mounted in the machine frame and it may be driven from any suitable source of power not shown herein. This main drive shaft 13 drives an auxiliary shaft 14 through gears 15, 16. The 45 several operating mechanisms other than the suction and air discharge devices are driven from this auxiliary drive shaft 14 as will hereinafter appear.

The carton supply mechanism will be first 50 described. A vertically arranged magazine 17 is provided for the collapsed cartons. An endless carrier is provided for moving the stack of collapsed cartons upwardly along the magazine 17 to bring the uppermost carton into position to be fed into the machine, which endless carrier comprises side chains 18 passing around upper and lower sprockets 19, 20, on cross shafts 21, 22, which chains are provided with shelves 23 arranged 55 to be brought into their supporting position while passing upwardly along the supply magazine 17, by means of studs or rollers 24, arranged to travel along a vertically arranged cam 25. An intermittent

65 movement is provided for the endless carrier by means of a ratchet wheel 26 engaged by a pawl 27 on a bar 28 provided with an eccentric connection 29 with the auxiliary drive shaft 14; the shaft 30 of the ratchet wheel 26 being connected to the upper shaft 70 21 of the endless carrier through a chain and sprocket connection 31, 32, 33.

The pawl 27 is rendered inoperative when the stack of collapsed cartons reaches the predetermined height with reference to the 75 feeding-in table 34 by the following device: The pawl 27 is provided with a bracket 35 which is connected to a rock arm 36 by a rod 37, which rock arm 36 is fixed to a rock shaft 38 mounted in suitable bearings on 80 the machine frame. This rock shaft 38 has fast thereon a rock lever 39 having a carton engaging device comprising a cross bar 40 and depending arms 41 arranged to engage the top of the stack of collapsed cartons. A 85 spring 42 and stop pin 43 yieldingly hold the depending arms 41 at the limit of their downward movement. This rock lever 39 is also provided with a roller 44 arranged to engage the upper combined feeding-in 90 and opening-up suction nozzle, to lift the arms 41 from their engagement with the top of the stack of collapsed cartons when the said nozzle is at the limit of its forward movement, as will hereinafter more fully 95 appear.

The suction means for feeding in and opening up the collapsed cartons, is constructed, arranged and operated as follows: The upper suction nozzle 45 is provided 100 with a feeding-in mouth 46 at its front end and a carton opening-up mouth 47 at its rear end, said mouths opening through the bottom 48 of the nozzle. The upper nozzle is also provided with a downwardly and forwardly inclined top 49 arranged to engage the roller 44 on the rock lever 39. This upper nozzle 45 has a carriage 50 which reciprocates horizontally in a right line in guides 51 in the side frames of the machine. 110 This upper nozzle is connected through a flexible pipe 52 to any suitable air exhausting means, not shown herein.

The lower nozzle 53 has an opening-up mouth 54 arranged to coact with the opening-up mouth 47 of the upper nozzle 45. This lower nozzle has a vertically reciprocating movement in a carriage 55 which reciprocates horizontally in a right line parallel with the carriage 50 in suitable guides 120 56. The nozzle 53 is provided with a cross pin 57 projecting through its side walls and through vertically elongated slots 58 in the carriage 55, which cross pin is provided with rollers 59 traveling in cam grooves 60. 125 These cam grooves 60 are horizontally arranged for a portion of their length from the rear toward the front and are then di-

rected upwardly and forwardly to cause the lower nozzle to approach and recede from the upper nozzle as the two nozzles approach and recede from the forward limits 5 of their movements.

The reciprocatory movements of the upper and lower nozzles are under the control of a rock lever 61 pivoted at 62 near the base of the machine, which rock lever is 10 engaged by an eccentric cam 63 on the auxiliary drive shaft 14. A rod 64 is connected at 65 to the upper nozzle carriage 50 and at 66 to the upper end of the rock lever 61. A rod 67 is connected at 68 to the lower nozzle carriage 55 and at its rear end has a loose 15 sliding engagement in the arms 69, 70, of a bracket 71 pivoted at 72 to the lever 61.

A lost motion connection, between the lower nozzle carriage and the rock lever 61, 20 is provided for as follows: A stop 73 is fixed to the rod 67, which stop is provided with rear and front shoulders 74, 75, arranged in in position to be engaged by an arm 76 depending from the rod 64 at the rear end 25 thereof. This stop 73 is furthermore provided with rear and front shoulders 77, 78, arranged to engage the opposite faces of the arm 70 of the bracket 71. This lost motion connection between the carriages of the upper and lower nozzles and the rock lever 61, 30 operates to bring the mouths 47 and 54 of the upper and lower suction nozzles opposite each other as they reach onehalf of their rearward travel; the remainder of 35 their rearward travel in this position being accomplished by the engagement of the arm 76 with the rear shoulder 74 of the stop 73.

While the mouths 47, 54, of the upper and lower suction nozzles are coacting to open 40 up a carton, the mouth 46 of the upper nozzle will be feeding the next succeeding collapsed carton from the stack rearwardly along the feed table 34 into a position immediately to the rear of a spring actuated 45 catch having fingers 79 projecting upwardly through slots 80 in the feed table 34.

To compensate for the arcs through which the corners of the cartons pass while opening and traveling with the movements, the 50 mouth 54 of the lower nozzle is permitted a slight rearward movement against the tension of a spring 81, which spring 81 will return the mouth 54 to its normal position in alignment with the lower nozzle. This 55 mouth 54 is furthermore provided with a spring-actuated stop 82 along its rear edge, which stop projects above the lower nozzle a sufficient distance to engage the rear lower edge of the carton to prevent the carton 60 from overrunning the mouth of the lower nozzle. When the opened-up carton is removed from between the opening-up mouths of the upper and lower suction nozzles, the stop 82 will be forced below the

upper plane of the lower nozzle but will immediately resume its operative position 65 when the carton has passed rearwardly beyond it.

The lower suction nozzle is connected to the exhaust pipe 52 through the pipe 83, it 70 being understood that there is a constant suction exerted through the upper and lower suction nozzles at all times.

The formers are denoted by 84 and they are caused to travel in an endless path and 75 are inserted into the opened-up carton by mechanical means at one point in their travel and the cartons, after the flaps at one end thereof have been folded and sealed, are blown from the formers at another point of their travel.

A vertically arranged former supply magazine 85 is located at the front of the machine and a vertically arranged pressure magazine 86 is located at the rear of the 85 machine, the tops of which magazines are connected by a bridge 87. The former supply magazine 85 has its lower end arranged in position to direct the bottommost former of the stack onto the top of a carriage 88 at 90 one side of the path of travel of the cartons, which carriage reciprocates horizontally in a right line on a frame bar 90. This carriage 88 is reciprocated from the rock lever 61 through a rod 91 connected at 92 to the 95 carriage 88 and at 93 to the stop 73 carried by the rod 67 of the lower suction nozzle 53. This carriage 88 is provided with a yielding gage 94 arranged to engage the rear side of the bottommost former when resting 100 on the carriage which is yieldingly held at the limit of its forward movement by means of a spring 95. A spring actuated latch 96 is pivoted at 97 to the carriage 88, the tail piece 98 of which latch serves as a stop to 105 yieldingly keep the end of the latch raised a certain distance above the surface of the carriage 88 in position to engage the front side of the bottommost former of the stack when resting upon the carriage 88, and is a 110 guide for the lateral movement of the former.

The means for moving the former laterally into the opened-up carton, as the carton and the former are traveling rearwardly, comprises a pusher plate 99 having a laterally 115 sliding connection with a transversely elongated slot 100 in the carriage 88, which pusher plate 99 carries a yielding pin 101 held by a spring 102 at the limit of its inward movement, which pin 101 is adapted to enter a 120 recess 103 in the front side of the former for accurately positioning the carton. This laterally movable pusher plate 99 is reciprocated from a stationary cam 104 which engages a stud or roller 105 carried by an arm 125 106, one end of which is connected at 107 to the plate 99 and the other end of which is hinged at 108 to the carriage 88.

The carriage 88 is provided with an extension 109 to which is hinged at 110 a platform 111. The free end of this platform is raised and lowered by means of a toggle lever connection 112, 113, a projecting arm 114 of which is arranged in position to be engaged by a stop 115 as the carriage reaches the limit of its forward movement for raising the platform and by a stop 116 as the carriage reaches the limit of its rearward movement for lowering the platform.

The opened carton, with its former inserted therein, is moved rearwardly from between the suction nozzles to a point beneath the bottom of the pressure magazine 86 by the bottom of the pressure magazine 86 by a reciprocating device comprising two plates 117, 118, provided with spring-pressed latches 119, 120, which are arranged to be depressed when the plates 117, 118, are moved forwardly beneath the opened-up carton and its former and are arranged to snap upwardly into position to engage the front side of the opened-up carton as the plates 117, 118, reach the limit of their forward movement. These plates 117, 118, reciprocate horizontally in a right line in suitable guides 121, 122, and the rear ends of the plates are connected by links 123, 124, to the depending arm 125 of a three-armed rock lever pivoted at 126 to the machine frame, another arm 127 of which lever is connected by a rod 128 to one arm 129 of a rock lever pivoted at 130 and the other arm 131, of which rock lever is connected by a rod 132 to an eccentric 133 on the auxiliary drive shaft 14.

One end of each former is provided with an uprising lip 134 and a recess 135. The lip 134 is arranged to travel in a groove 136 of an upper track rail 137 and a lower track rail 138 on the guide 122 is arranged to enter the recess 135 in the former to hold the former in position as the former and its carton are moved rearwardly from between the suction nozzles to a position beneath the pressure magazine.

While the former is thus held, the flaps at the opposite end of the carton are subjected to the first three folding operations as follows: As the carton and its former are moved rearwardly, the flap 10 is folded by the stationary folding cam 139 and at substantially the same time the flap 11 is folded by the movable folding device, which device comprises a swinging arm 140 hinged at 141, which arm is held yieldingly at the limits of its outward and inward movements by a spring 142 connected at 144 to a lug of the arm 140. A tripper arm 145 is fixed to rock with the arm 140 and is arranged in position to be engaged by and swung rearwardly by a lug 146 on the nozzle carriage 50 and is adapted to be swung forwardly by a lug 147 carried by the connecting rod 64. The flap 12 is folded upwardly by the stationary cam

148. As the carton and its former continue their rearward movement, the inner face of the flap 9 passes over a paster disk 149 of a paste fountain 150, the shaft 151 of which disk is driven from a shaft 152 through a chain and sprocket connection 153, 154, 155. The shaft 152 is provided with a pulley 156 driven from any suitable source of power, not shown herein.

The three folded flaps are maintained in their folded position by their engagement with the vertical face of the cam 148.

The fourth fold and sealing of the flaps at the closed end of the carton is accomplished by the upward movement of the carton and former into the pressure magazine to be immediately described.

The pressure magazine is open at its bottom and top and it is provided with an unyielding front wall 157, a yielding right side wall 158, a movable left side wall 159, and a movable back wall 160. The side wall 158 is yieldingly held at the limit of its inward movement by springs 161. The left side wall is moved inwardly and outwardly by toggle lever joint connections 162, 163, with a vertically arranged rock shaft 164, guides 165 being provided for guiding the side wall in its movements. The back wall 160 is moved forwardly and rearwardly by toggle joint connections 166, 167, with a vertically arranged rock shaft 168, a guide 169 being provided for guiding the wall 160 in its forward and rearward movements. The shafts 164, 168, are connected to rock together by means of rock arms 170, 171, and their connecting rod 172. The rock shaft 164 is provided with a two-armed lever 173, one arm 174 of which is arranged in position to be engaged by a cam 175 on the former carriage 88 to rock the shaft 164 in one direction, and the other arm 176 of said lever being arranged in position to be engaged by a yielding cam 177 also carried by the carriage 88 for rocking the shaft 164 in the other direction.

A vertically reciprocating plunger head 178 has its rod 179 resting on the end of the arm 129 of the lever 129, 130, 131. This rod 179 reciprocates vertically in bearings 180 of the frame. The head 178 is held from turning by side bars 181 connecting the head 178 with the arm 129 upon opposite sides of the plunger rod 179. The movement of the parts are so timed that the side and back walls 159 and 160 are released from their pressure engagement with the stack of cartons and formers as the plunger rises and meets the bottommost former to force the bottommost carton and former up into the pressure magazine. This upward movement of the carton will fold its fourth flap downwardly onto the other folded flaps and seal the same. The movable side and back walls of the pressure magazine will be moved

into pressing engagement with the stack of cartons and formers to support the stack before the plunger starts on its downward movement into position to receive the next 5 succeeding carton and former above the same.

A swinging latch 182 is hinged at 183 to a bracket 184 at the top of the pressure magazine, which latch is arranged in position

10 to engage the raised lip 184 on the projecting end of the former and tilt the other end of the former upwardly. While the former is held in its tilted position, the carton is blown from the former by a blast of air 15 from a nozzle 185 arranged in position to direct the blast of air through the tubular center 186 of the former against the folded and sealed end of the carton. The air pressure is supplied to the ejector nozzle 185

20 through a pipe 187 leading from a source of pressure supply, not shown. Intermittent blasts are provided for by a spring actuated valve 188 in the pipe 187 under the control of a handle 189 arranged in position to be 25 engaged by the reciprocating carriage 88 to open to the nozzle when the carriage 88 reaches the limit of its rearward movement.

After the carton has been ejected from the topmost former, the former is moved 30 forwardly along the bridge 87 by a slide 190 reciprocating in a track 191 on a bracket 192, which slide is connected by a rod 193 to the upper arm 194 of the three-armed lever heretofore described pivoted at 126.

35 The front wall of the former supply magazine 85 at its upper end is provided with a yielding plate 195 for guiding the formers downwardly into the magazine.

It is to be understood that these formers 40 84 are entirely separate one from another and that a sufficient number of these formers are utilized to provide for a continuous contacting series of formers from the lower end of the pressure magazine 85 upwardly 45 therethrough, along the bridge 87 and downwardly through the former supply magazine 85 to the bottom thereof so that a former is supplied for each carton.

A general description of the operation of 50 the different mechanisms of the machine on the cartons and formers is as follows: The collapsed cartons are fed upwardly along the carton supply magazine 17 by the intermittent movement of the endless carrier. As 55 the upper suction nozzle 45 reaches the limit of its forward movement, its mouth 46 will engage the topmost carton by suction effect and the carton will be carried over the table 34 past the fingers 79 of the catch at the 60 limit of the rearward movement of the suction nozzle 45. The finger 79 engages the collapsed carton and holds it on the table 34 until the mouth 47 in turn engages it at the 65 limit of the next forward movement. In the meantime, the suction mouths 47 and 54

of the upper and lower nozzles are caused to engage the upper and lower sides of the previously fed-in carton and move the same inwardly and, at the same time, open up the carton.

As the nozzles reach one-half of their rearward movement, a former, which has been deposited onto the reciprocating carriage 88 from the former supply magazine 85, between the gage 94 and the spring actuated latch 96, will be forced into the opened-up carton by the inward movement of the pusher plate 99. The registering pin 101 will engage the end of the carton by passing 70 into the recess 103 in the former, the carton 75 being thereby held in position on the former so that the flaps at the opposite end of the carton will be properly folded on the scoring lines.

The further rearward movement of the 85 carton and its former will cause the folding of the flaps 10, 11, 12, further rearward movement being accomplished by the engagement of the latch 119, 120, therewith and the rearward movement of the latch 90 carrying plates 117, 118, the flap 9 being carried over and in contact with pasteur disk 149. When the carton and its former reaches a position beneath the bottom of the pressure magazine 86 and above the plunger 178, the walls 159, 160, of the pressure magazine are released and the plunger 178 moves upwardly thus forcing the carton and its former upwardly into the pressure magazine 95 and thereby folding the last flap 9 downwardly and sealing all of the flaps at that 100 end of the carton. The movable walls 159, 160, of the pressure magazine are then brought into pressing engagement with the carton, thus serving to properly square up 105 the carton and seal the end of the same. It is to be understood that the carton and its former in their step by step upward movement are subjected to a series of these pressures so that by the time the carton and its 110 former reaches the top of the pressure magazine, a very complete and accurate sealing of the closed end of the carton is accomplished.

As the carton and its former is pushed above the top of the pressure magazine, the latch 182 will tilt the former and, at the same time, a blast of air from the ejector 185 passing through the former and acting against the closed end of the carton will blow the carton from the former. As 115 soon as this is accomplished, the slide 190 will push the former along the bridge 87 toward the former supply magazine 85. The former will then proceed step by step along the bridge and downwardly along the magazine 85 into position for use in connection 120 with a succeeding carton.

As the carriage 88 reaches the limit of its rearward movement, the platform 111 is lowered by the engagement of the stop 116 130

with the arm 114 of the toggle joint connection. As the carriage reaches the limit of its forward movement, the stop 115 will, by its engagement with the arm 114, raise the platform 111. When the carriage and bottom former, as previously described, start on their rearward movement, the platform 111 will engage the bottom of the next former and lower it gradually by its passage 10 along the inclined plane thus provided, to the surface of the carriage 88 in position to be engaged on the next rearward movement of the carriage.

It will also be understood that if the collapsed cartons are being fed too rapidly upwardly along their magazine 17, the feeding of the cartons will be temporarily stopped by the coaction of the topmost carton with the arms 41 of the releasing device.

20 It will also be seen that these arms 41 are raised from their position on the top of the stack of collapsed cartons, by the engagement of the upper suction nozzle with the roller 44 at the time the suction nozzle 25 is engaging the uppermost collapsed carton for feeding the same into the machine.

What we claim is:

1. In a machine of the character described, suction means for feeding in and opening up 30 a collapsed carton, a former and means for forcing the former into the opened carton.

2. In a machine of the character described, suction means for feeding in and opening up a collapsed carton, a traveling former 35 and means for forcing the former into the opened carton at a predetermined point in its travel.

3. In a machine of the character described, suction means for feeding in and opening up 40 a collapsed carton, a traveling former, means for forcing the former into the opened carton at a predetermined point in its travel, and mechanisms operating to fold and seal the flaps at one end of the carton.

45 4. In a machine of the character described, suction means for feeding in and opening up a collapsed carton, a traveling former, means for forcing the former into the opened carton at a predetermined point in its travel, 50 mechanisms operating to fold and seal the flaps at one end of the carton, and means for exerting pressure on the sides and sealed end of the carton.

5. In a machine of the character described, suction means for feeding in and opening up 55 a collapsed carton, a former and means for forcing the former into the carton while it is held open by the suction means.

6. In a machine of the character described, 60 suction means for feeding in and opening up a collapsed carton, a traveling former and means for forcing the former into the carton while it is held open by the suction means at a predetermined point in the travel 65 of the former.

7. In a machine of the character described, suction means for feeding in and opening up a collapsed carton, a traveling former, means for forcing the former into the carton while it is held open by the suction means 70 at a predetermined point in the travel of the former, and mechanisms operating to fold and seal the flaps at one end of the carton.

8. In a machine of the character described, 75 suction means for feeding in and opening up a collapsed carton, a traveling former, means for forcing the former into the carton while it is held open by the suction means 80 at a predetermined point in the travel of the former, mechanisms operating to fold and seal the flaps at one end of the carton, and means for exerting pressure on the sides and sealed end of the carton.

9. In a machine of the character described, 85 suction means for feeding in and opening up a collapsed carton, a traveling former, means for forcing the former into the opened carton at one point in its travel, mechanisms operating to fold and seal the 90 flaps at one end of the carton and means for removing the carton from the former at another point in its travel.

10. In a machine of the character described, 95 suction means for feeding in and opening up a collapsed carton, a traveling former, means for forcing the former into the opened carton at one point in its travel, mechanisms operating to fold and seal the 100 flaps at one end of the carton and fluid pressure means for blowing the carton off the former at another point in its travel.

11. In a machine of the character described, 105 suction means for feeding in and opening up a collapsed carton, a traveling former, means for forcing the former into the opened carton at one point in its travel, mechanisms operating to fold and seal the flaps at one end of the carton, means for exerting pressure on the sides and sealed end 110 of the carton, and means for removing the carton from the former at another point in its travel.

12. In a machine of the character described, 115 suction means for feeding in and opening up a collapsed carton, a traveling former, means for forcing the former into the opened carton at one point in its travel, mechanisms operating to fold and seal the flaps at one end of the carton, means for exerting pressure on the sides and sealed end 120 of the carton, and fluid pressure means for blowing the carton off the former at another point in its travel.

13. In a machine of the character described, 125 a traveling former, suction means for feeding in and opening up a collapsed carton comprising two suction nozzles, one operable to feed in the collapsed carton and both operable to open up the carton, and 130

means for forcing the former into the opened carton.

14. In a machine of the character described, suction means for feeding in and opening up a collapsed carton comprising two reciprocating suction nozzles, one being movable forwardly and rearwardly in a right line and the other being movable forwardly and rearwardly toward and away from the first-named nozzle.

15. In a machine of the character described, a traveling former, suction means for feeding in and opening up a collapsed carton comprising two reciprocating suction nozzles, one being movable forwardly and rearwardly in a right line and the other being movable forwardly and rearwardly toward and away from the first-named nozzle, and means for forcing the former into the opened carton.

16. In a machine of the character described, a magazine, means for moving a carton carrying former to the magazine, means for folding three flaps at one end of the carton while traveling toward the magazine, means for forcing the carton into the magazine to fold the fourth flap, means for tilting the former as it emerges from the magazine and means for removing the carton from the tilted former.

17. In a machine of the character described, a magazine, means for moving a carton carrying former to the magazine, means for folding three flaps at one end of the carton while traveling toward the magazine, means for forcing the carton into the magazine to fold the fourth flap, means for exerting pressure on the sides and closed end of the carton while within the magazine, means for tilting the former as it emerges from the magazine and means for removing the carton from the tilted former.

18. In a machine of the character described, a magazine, means for moving a carton carrying former to the magazine, means for folding three flaps at one end of the carton while traveling toward the magazine, means for forcing the carton into the magazine to fold the fourth flap, and fluid pressure means for ejecting the carton from the former as it emerges from the magazine.

19. In a machine of the character described, a magazine, means for moving a carton carrying former to the magazine, means for folding three flaps at one end of the carton while traveling toward the magazine, means for forcing the carton into the magazine to fold the fourth flap, means for exerting pressure on the sides and closed end of the carton while within the magazine, and fluid pressure means for ejecting the carton from the former as it emerges from the magazine.

20. In a machine of the character described, a magazine, means for moving a

carton carrying former to the magazine, means for folding three flaps at one end of the carton while traveling toward the magazine, means for forcing the carton into the magazine to fold the fourth flap, means for 70 tilting the former as it emerges from the magazine, and fluid pressure means for ejecting the carton from the tilted former.

21. In a machine of the character described, a magazine, means for moving a 75 carton carrying former to the magazine, means for folding three flaps at one end of the carton while traveling toward the magazine, means for forcing the carton into the magazine to fold the fourth flap, means 80 for exerting pressure on the sides and closed end of the carton while within the magazine, and means for tilting the former as it emerges from the magazine, and fluid pressure means for ejecting the carton from the 85 tilted former.

22. In a machine of the character described, a magazine, means for moving a carton carrying former to the magazine, means for folding three flaps and applying 90 adhesive to the fourth flap at one end of the carton while traveling toward the magazine and means for forcing the carton into the magazine and thereby fold and seal the fourth flap.

23. In a machine of the character described, a magazine, means for moving a carton carrying former to the magazine, means for folding three flaps and applying adhesive to the fourth flap at one end of the 100 carton while traveling toward the magazine, means for forcing the carton into the magazine and thereby fold and seal the fourth flap, and fluid pressure means for ejecting the carton from the former as it 105 emerges from the magazine.

24. In a machine of the character described, a magazine, means for moving a carton carrying former to the magazine, means for folding three flaps and applying 110 adhesive to the fourth flap at one end of the carton while traveling toward the magazine, means for forcing the carton into the magazine and thereby fold and seal the fourth flap, means for exerting pressure on 115 the sides and sealed end of the carton while within the magazine, and fluid pressure means for ejecting the carton from the former as it emerges from the magazine.

25. In a machine of the character de- 120 scribed, a magazine, means for moving a carton carrying former to the magazine, means for folding three flaps and applying adhesive to the fourth flap at one end of the 125 carton while traveling toward the magazine, means for forcing the carton into the magazine and thereby fold and seal the fourth flap, means for tilting the former as it emerges from the magazine and means for removing the carton from the tilted former. 130

26. In a machine of the character described, a magazine, means for moving a carton carrying former to the magazine, means for folding three flaps and applying adhesive to the fourth flap at one end of the carton while traveling toward the magazine, means for forcing the carton into the magazine and thereby fold and seal the fourth flap, means for exerting pressure on the sides and sealed end of the carton while within the magazine, means for tilting the former as it emerges from the magazine and means for removing the carton from the tilted former.
27. In a machine of the character described, a magazine, means for moving a carton carrying former to the magazine, means for folding three flaps and applying adhesive to the fourth flap at one end of the carton while traveling toward the magazine, means for forcing the carton into the magazine and thereby fold and seal the fourth flap, means for tilting the former as it emerges from the magazine and fluid pressure means for ejecting the carton from the tilted former.
28. In a machine of the character described, a magazine, means for moving a carton carrying former to the magazine, means for folding three flaps and applying adhesive to the fourth flap at one end of the carton while traveling toward the magazine, means for forcing the carton into the magazine and thereby fold and seal the fourth flap, means for exerting pressure on the sides and sealed end of the carton while within the magazine, means for tilting the former as it emerges from the magazine and fluid pressure means for ejecting the carton from the tilted former.
29. In a machine of the character described, a former supply magazine, a pressure magazine and coacting mechanisms operable to move the formers in an endless path through the two magazines, to feed in and open up collapsed cartons, to force the formers into their respective cartons, to fold and seal the flaps at one end of the cartons and to eject the cartons from their formers.
30. In a machine of the character described, a former supply magazine, a pressure magazine and coacting mechanisms operable to move the formers in an endless path through the two magazines to feed in and open up collapsed cartons, to force formers into their respective cartons, to fold and seal the flaps at one end of the cartons, to exert pressure on the sides and sealed end of the cartons while passing through the pressure magazine from their formers after they leave the pressure magazine.
31. In a machine of the character described, a collapsed carton supply magazine, a former supply magazine, a pressure magazine and coacting mechanisms operable to move the formers in an endless path through the two magazines to feed in and open up collapsed cartons, to force the formers into their respective cartons, to fold and seal the flaps at one end of the cartons, to exert pressure on the sides and sealed end of the cartons while passing through the pressure magazine, and to eject the cartons from their formers after they leave the pressure magazine.
32. In a machine of the character described, a collapsed carton supply magazine, a former supply magazine, a pressure magazine, and coacting mechanisms operable to move the formers in an endless path through the two magazines, to feed the collapsed cartons from the carton supply magazine and open up the cartons, to force the formers into their respective cartons to fold and seal the flaps at one end of the cartons, to exert pressure on the sides and sealed end of the cartons while passing through the pressure magazine, and to eject the cartons from their formers after they leave the pressure magazines.
33. In a machine of the character described, a former supply magazine, a pressure magazine and coacting mechanisms operable to feed in and open up the cartons, to feed the formers from the bottom of their supply magazine and introduce them into the cartons, to fold and seal the flaps at one end of the cartons, to feed the cartons and their formers to the bottom and through the pressure magazine to eject the cartons from their formers and to return the formers to the top of their supply magazine.
34. In a machine of the character described, a former supply magazine, a pressure magazine and coacting mechanisms operable to feed in and open up the cartons, to feed the formers from the bottom of their supply magazine and introduce them into the cartons, to fold and seal the flaps at one end of the cartons, to feed the cartons and their formers to the bottom and through the pressure magazine, to exert pressure on the sides and sealed ends of the cartons while passing through the pressure magazine to eject the cartons from their formers and to return the formers to the top of their supply magazine.
35. In a machine of the character described, a former supply magazine, a pressure magazine, a bridge connecting the tops of the pressure and former magazines and coacting mechanisms operable to feed in and open up the cartons, to feed the formers from the bottom of their supply magazine and introduce them into the cartons, to fold and seal the flaps at one end of the cartons, to feed the cartons and their formers to the bottom and through the pressure magazine, to eject the cartons from their formers and to return the formers along the bridge to their supply magazine.
36. In a machine of the character described, a former supply magazine, a pres-

- sure magazine, a bridge connecting the tops of the pressure and former magazines and coacting mechanisms operable to feed in and open up the cartons, to feed the formers 5 from the bottom of their supply magazine and introduce them into the cartons, to fold and seal the flaps at one end of the cartons, to feed the cartons and their formers to the bottom of and through the pressure magazine 10 to exert pressure on the sides and sealed ends of the cartons while passing through the pressure magazine, to eject the cartons from their formers and to return the formers along the bridge to their supply magazine.
- 15 37. In a machine of the character described, a former supply magazine, a pressure magazine, a bridge connecting the tops of the pressure and former magazines, and coacting mechanisms operable to feed in and open up the cartons, to feed and introduce the formers into the cartons, to fold and seal the flaps at one end of the cartons, to feed the cartons and their formers to and through the pressure magazine, to tilt the 20 carton carrying formers at the top of the pressure magazine, to eject the cartons from the tilted formers and to return the formers along the bridge to their supply magazine.
- 25 38. In a machine of the character described, a former supply magazine, a pressure magazine, a bridge connecting the tops of the pressure and former magazines and coacting mechanisms operable to feed in and open up the cartons, to feed and introduce the formers into the cartons, to fold and seal the flaps at one end of the cartons, to feed the cartons and their formers to and through the pressure magazine, to exert pressure on 30 the sides and sealed ends of the cartons while passing through the magazine, to tilt the carton carrying formers at the top of the pressure magazine, to eject the cartons from the tilted formers and to return the formers along the bridge to their supply magazine.
- 35 39. In a machine of the character described, a pressure magazine having movable side and end walls, means for feeding carton carrying formers successively into position beneath the magazine, a reciprocating plunger for forcing the carton carrying formers upwardly step by step into the magazine, means operated to move the movable side and end walls into and out of pressure contact with said carton carrying formers, means for tilting the formers as they reach the top of the magazine and means for ejecting the cartons from the tilted formers.
- 40 40. In a machine of the character described, a pressure magazine having movable side and end walls, means for feeding carton carrying formers successively into position beneath the magazine, a reciprocating plunger for forcing the carton carrying formers upwardly step by step into the mag-
- azine, means operated to move the movable side and end walls into and out of pressure contact with said carton carrying formers, means for tilting the formers as they reach the top of the magazine and fluid pressure 70 means for ejecting the cartons from the tilted formers.
41. In a machine of the character described, suction means arranged to simultaneously feed in a collapsed carton and open up the preceding fed-in carton, and means for feeding in a former and forcing it into the opened carton. 75
42. In a machine of the character described, means for feeding in and opening up a collapsed carton, a former supply magazine, a carriage arranged to reciprocate longitudinally beneath the former supply magazine for feeding in a former, and laterally movable means for forcing the formers 80 into the opened carton. 85
43. In a machine of the character described, means for feeding in and opening up a collapsed carton, a former supply magazine, a carriage arranged to reciprocate longitudinally beneath the former supply magazine for feeding in a former, and laterally movable means on the carriage for forcing the former into the opened carton. 90
44. In a machine of the character described, suction means for feeding in and opening up a collapsed carton, a former supply magazine, a carriage arranged to reciprocate longitudinally beneath the former supply magazine and laterally movable 100 means for forcing the former into the opened carton. 95
45. In a machine of the character described, suction means for feeding in and opening up a collapsed carton, a former supply magazine, a carriage arranged to reciprocate longitudinally beneath the former supply magazine and laterally movable means on the carriage for forcing the former into the opened carton. 105 110
46. In a machine of the character described, means for feeding in and opening up a collapsed carton, a carriage arranged to reciprocate longitudinally for feeding in a former, laterally movable means for forcing the former into the opened carton and a carton positioning device carried by said laterally movable means. 115
47. In a machine of the character described, means for feeding in and opening up a collapsed carton, a carriage arranged to reciprocate longitudinally for feeding in a former, laterally movable means on the carriage for forcing the former into the opened carton and a carton positioning device carried by said laterally movable means. 120
48. In a machine of the character described, a pressure magazine having movable side and back walls, a reciprocating 125 130

former feeding carriage and means carried thereby for controlling the movements of the said side and back walls of the pressure magazine.

- 5 49. In a machine of the character described, a traveling carton carrying former, a reciprocating former feeding carriage and

a fluid actuated means under the control of the movement of the carriage for ejecting the carton from the former.

In testimony that we claim the foregoing as our invention, we have signed our names.

ERNEST A. SCHROEDER.

JOHN N. TOOKER.
